UNITED STATES PATENT OFFICE.

WILLIAM W. HARRIS, OF NEW YORK, N. Y.

GRAVITY-OPERATED FIGURE TOY.

Application filed July 7, 1928. Serial No. 650,181.

This invention relates to toys.

More particularly, this invention relates to a toy embodying an acrobatic stunt wherein the one or more figures representing the participants of the acrobatic stunt being set in motion mechanically by means of a marble or the like.

In the particular form of the invention as disclosed in the drawings, the several figures representing the participants are pivotally or otherwise arranged to be moved in similitude of animated persons, animals and the like, such as trapeze acrobats, a clown mounted on a donkey and teaming with one or more other clowns when desired or with other movable figures, the motion of which is set about indirectly by the motion of the figures actuated by the marble. Such figures are mounted on a suitable support such as a background representing the arena of a circus or the like, and a runway is provided for the marbles; one or more figures are respectively provided with pockets for momentarily receiving a marble, or for retaining the marble. Such figure or figures upon receiving a marble are actuated and retain the marble in their actuated position. Combined with such figures, there is arranged, when desired, other movable figures, the motion of which is set about indirectly by the motion of the figures actuated by the marble. Preferably the figures are arranged so that successive marbles produce varying motions for the figures.

Further features and objects of the invention will be more fully understood from the following detail description and the accompanying drawings in which

Fig. 1, is a front elevation of a toy illustrative of a series of circus acrobatic stunts, including a runway for the marbles, and embodying one form of my invention;

Fig. 2, is a detail top plan view of the entry opening for the marbles, leading to the runway shown in Fig. 1;

Fig. 3, is a detail sectional elevation on line 3—3, of Fig. 1;

Fig. 4, is a detail sectional elevation on line 4—4 of Fig. 1;

Fig. 5, is a detail sectional elevation on line 5—5 of Fig. 1;

Fig. 6, is a detail side elevation on an enlarged scale, of a form of pocket for receiving the marble indicated in Fig. 1, and

Fig. 7, is a sectional elevation on line 7—7 of Fig. 6. 55

Referring to the drawings, the toy comprises a suitable support such as an open face box arranged to be placed in vertical position when supported on its base 11. The back 12, see Figs. 2, 3, 4 and 5, the base 11 and the upper strip 13 may be formed of wood and nailed or otherwise secured to one another for rigidity.

The runway or chute 14, of tin or the like, 65 may be located at one side within the box 10, and an opening 15 provided in the top strip 13 to afford entry of the marbles 16, 17 etc., for delivery to the chute 14 and subsequent actuation of the figures. 70

Cooperating with the marbles, I have arranged the figure 18, illustrating in this instance, a female figure 18^a, and a male figure 18^b, associated on a trapeze such figure may be formed of heavy board, cardboard, thin metal or the like, as a single mechanical element, and pivoted at 19, see Figs. 1 and 3, as by means of the nail 20 passing through a suitable opening in the strip 18, thence through the collar 21 of wood and lodged at 22 in the back board 12. The figure 18 is preferably arranged to be overweighted at its lower portion 18^b, sufficiently to return the upper portion 18^a to the normal position of the figure 18 shown in full outline in Fig. 1; but not sufficiently overweighted to prevent the figure 18 from being swung, when a marble 16 has been "caught" in the hands of the female figure 18^a, from its normal position in full outline to its actuated position indicated in dash outline. The stop 23, see Fig. 1, is provided for limiting the extreme movement of the swing of figure 18. 85

The figure 25, represents a donkey pivotally mounted at 26, on its fixed leg portion 27, which may be carried out similarly as the pivotal arrangement described in reference to the figure 18. On the donkey 25 is pivotally mounted the figure 28, of a clown; the pivot of the clown 28 to the donkey 25 is indicated at 29. The clown holds his cap 30 in a form of a receiver for a marble. 90

As will be viewed in Fig. 4, the detail mechanical elements of the donkey 25 and the clown 28 are given in greater detail. The figure 27 may be secured to the block of wood 31, or the like, and the pivot pin 32 for the pivot connection 26 may be lodged in the 100 105

2
block 31. The figure portion 28 is pivoted on the pivot pin 32 at the aforesaid location 26. The cap 30 of the clown 28 is in the form of a cone of cardboard, sheet metal, 5 tin or the like.

The pivot connection 29 may be in the form of a short pin, the opposite ends of which are swaged, to provide free pivotal movement but devoidance of material lateral swaying.

The figure 35 represents an elephant pivotally mounted at 36, on the figure 37, representing a pedestal. The pedestal figure 37 may be made of cardboard or the like, and 15 secured to the block 38, see Fig. 5. The pivotal connection 36 of the figure 35, of cardboard or the like, may be effected by means of the headed pin 36, lodged in the back board 12. The figure 35, is of an indirectly 20 actuated type, as will be shown more fully hereinafter, and its motion is associated by the provision of a pendulum like construction embodying the weight 39 secured to the arm 40, of tin or the like, and connected at 25 41 to the elephant figure 35. Ruggedness of such construction is secured by the provision of the collar 42 located about the pivot pin 37 and to which the arm 40 is secured. As 30 one form of receiving a marble, I have indicated a hand portion 45 at one side, see Figs. 3, 6 and 7, and a similar hand portion 46 at the opposite side, respectively secured to the arm portions 47, 48, connected to or integral with the figure 18^a. A retaining piece 49 of 35 tin, stiffened pasteboard, or the like, preferably comprising the longer rearward portion 50 and the shorter forward portion 51. Such retaining member 49 may be stamped by the use of a die from sheet metal or the like, and 40 connected by rivets 52, 53, to the supporting arm portions 47, 48.

Co-acting with the donkey and clown figure, I also provide an additional clown figure 55, pivotally mounted at 56, by means of a pin or the like, lodged in the back board 12, similarly as the pivot construction 19. The hands 57 of the clown 55 are arranged to receive a marble and may be constructed of spaced cardboard strips disposed at an angle to one another, or of the form shown by the hands 45, 46, and retaining member 49, as forming the arm receiving member of the figure 18^a. The clown 55 is overweighted at its lower portion 58 and the stop 59 provided to hold the clown 55 in its normal position; however, upon the clown 55 receiving 55 a marble, the overweight is sufficiently less to allow the marble, while retained in the arm portion 57 of the clown 55, to tilt the clown forwardly toward the donkey 25.

Having the above particulars in mind, upon dropping a marble into the opening 15, the marble rolls down its chute 14, and is received within the pocket formed by the 60 hands 45, 46 and retaining member 49. The

weight of the marble causes the figure 18 to swing counter clockwise as viewed in Fig. 1, until the figure 18 is brought to its dash outline position, at which position the marble, now denoted 16^a, drops from the hand pocket of the figure 18^a, into the clown's hat 30, whereupon the clown 28 and his hat 30 are tilted clockwise, thereafter causing the donkey 25 to be also tilted clockwise until the aforesaid figures assume the dash outline indicated in Fig. 1, in which movement, the marble, now designated 17, by reason of the change of position of the hat 30, drops from the hat 30 into the hand pocket 57 of the clown 55, whereupon the clown 55 is tilted counter clockwise and in sufficient time to lodge the marble 17^a between the head 60 of the donkey 25, and the hand portion 57 of the clown 55 now in its dash outline position and retain the donkey 25, mounted by its 85 clown 28, and the clown 55 in their respective actuated positions shown in dash outline.

The rotation of the figure 18 in the interim causes its lower portion 18^b to strike the elephant figure 35, which is thereupon 90 set into pendulating motion. Upon the dropping of the marble at the position 16^a, the overweight of the figure portion 18^b, causes the figure 18 to be returned to its normal or vertical position.

Upon dropping of a second marble into the opening 15, thence down the chute 14, such second marble is received within the hand pocket 45, 46, 49, causing figure 18 to be similarly tilted counter clockwise, but 100 in the interim, the clown 28 has been moved to and retained in its actuated position, i. e., its dash outline position 28^a, and such second marble is caught in the pocket, formed between the projection 62—representing the 105 furbelow or the like of the clown's garment—and the back 63 of the clown, whereupon the figure 28 is overbalanced by the second marble in counter clockwise rotation, causing the clown 28 and the donkey 25 110 to be returned to normal position, whereupon the first marble 17^a, drops from the hand portion 57 of the clown 55, and the clown 55 is returned to its normal position. Thereupon, the first marble and the 115 second marble drop to the upper face of the bottom strip 11, preparatory to being passed through the opening 15 for returning travel along the chute 14 to again actuate the figures to effect a repetition of the aforesaid 120 operations.

Whereas, I have described my invention by reference to specific forms thereof it will be understood that many changes and modifications may be made without departing from the spirit of the invention.

I claim:

1. In a gravity operated figure toy, the combination of an upright support, a base for the supports, a runway for marbles on 120

said background, a figure pivotally mounted on said support and having a receiving and holding device positioned to receive a marble when delivered from said runway, said figure being pivoted slightly above its center of gravity, said marble receiving and holding device serving to transfer the marble while said figure is rotated from its upright position to a position horizontally below its pivot, a second figure pivotally mounted on said support and including a device for receiving a marble, said second-named figure being pivoted at a point substantially below its center of gravity, said marble receiving device being positioned to receive a marble after transfer thereto by said marble receiving and holding device of said first-named figure, and a third figure pivotally mounted on said support and disposed to normally hold said second figure in a predetermined position, whereby upon placing a marble in said runway, said marble successively rotates said first-named figure, and is transferred by said first-named figure 20 to said second-named figure, and said second-named figure is rotated directly by said marble and indirectly rotates said third-named figure.

2. In a gravity operated figure toy, the combination of an upright support, a base for the support, a runway for marbles on said background, a figure pivotally mounted on said support and having a receiving and holding device positioned to receive a marble when delivered from said runway, 35 said figure being pivoted slightly above its center of gravity, said marble receiving and holding device serving to transfer the marble while said figure is rotated from its upright position to a position horizontally below its pivot, a second figure pivotally mounted on said support and including a device for receiving a marble, said second-named figure being pivoted at a point substantially below its center of gravity, said 40 marble receiving device being positioned to receive a marble after transfer thereto by said marble receiving and holding device of said first-named figure, a third figure pivotally mounted on said support and disposed to normally hold said second figure in a predetermined position, whereby upon placing a marble in said runway, said marble successively rotates said first-named figure, and is transferred by said first-named figure 45 to said second-named figure, and said second-named figure is rotated directly by said marble and indirectly rotates said third-named figure and a fourth figure pivotally mounted on said support, said fourth figure 50 being disposed to be encountered and rotated by one of said figures during a portion of the rotation of such one figure.

In testimony whereof I have signed this specification this 30th day of June 1923.

WILLIAM W. HARRIS.
